ROTARY INTAGLIO DOCTOR MECHANISM

Charles A. Harless, Riverside, Conn., assignor to
R. Hoe & Co., Inc., New York, N. Y., a corpora-
tion of New York

Application December 14, 1948, Serial No. 65,155

11 Claims. (Cl. 101—157)

1

This invention relates to rotary intaglio doctor mechanisms.

It is an object of the invention to provide improved doctor mechanism by means of which the doctor is moved into and out of operating relation to the cylinder and may be adjusted with certainty and safety.

A further object of the invention is to provide doctor operating mechanism of the type indicated in conjunction with doctor pressure regulating mechanism of a yieldable spring operated type.

The mechanism of the present invention is an improvement upon the doctor mechanism shown and described in Huck application Serial No. 60,075 filed November 15, 1948, for Doctor Mechanism.

With the foregoing and other objects in view, which will appear as the description proceeds, the invention resides in the combinations and arrangements of parts and in the details of construction hereinafter described and claimed.

In the drawing:

Figure 1 is an end elevational view of the doctor mechanism embodying the invention in a preferred form of embodiment, certain parts being omitted for clarity in the showing;

Figure 1A is a detail view of a portion of Figure 1 showing certain parts omitted from Figure 1;

Figure 2 is a plan view of the doctor mechanism of Figure 1;

Figure 3 is a rear elevational view of the doctor mechanism of Figure 1;

Figure 4 is a section on the line 4—4 of Figure 2; and

Figure 5 is a section on the line 5—5 of Figure 4.

In Figure 1 there is indicated an intaglio printing cylinder 1 carried on a shaft 2 which is journaled as usual in the press frames. A housing 3 may enclose the major part of the cylinder 1. The doctor blade 4 is carried in a doctor holder 5 having an angle 6. The doctor blade assembly may be of any desired type and hence is not shown and described in detail herein. The mechanism by which the doctor blade assembly 5 is supported comprises a bar 7 extending the length thereof and having a slot to receive the angle 6, the doctor blade assembly being held therein as by means of clamps 8. The bar 7, in turn, is fastened to a pair of arms 9 formed as hollow housings and generally similar to the corresponding arms of the Huck application before referred to. These arms are pivotally carried by means of bearings 10 on a shaft 11, which in turn is carried in bearing 12 of posts or pedestals

2

13 which are fixed to the usual sliding carriage 14. The sliding carriage 14 is supported on tracks 15, which are attached to the machine frames 16 (Figs. 2 and 3), and is reciprocated by a doctor reciprocating mechanism 17 through a connecting link 18 and stub shaft and bearing assembly 19.

Within each housing 9 is positioned an arm 20 which is fixed to the shaft 11. The doctor pressure is regulated by adjusting springs reacting between arms 9 and 20 as in the Huck application and shaft 11 is rotated for moving the doctor into and out of operating position by means of a worm wheel unit 21, as will be hereinafter described in detail.

Assuming shaft 11 to have been set into operating position as shown in Figure 1, the operation of the parts is as follows: Springs 25 received within a bore of each arm 20 react against the rear wall of each pivoted housing 9 for counterbalancing the weight of the doctor assembly, the bar 7 and the arms 9. The pressure of springs 25 may be adjusted by means of threaded members 26, access thereto being provided through openings 27 in the housings 9. Further springs 28 are carried on slidable poppet rods 29 which are received within sockets 30. Each spring 28 acts between a member 31 attached to a rod 29 and the material of its housing 9 surrounding socket 30. An adjusting rod 32 is threadably carried in the upper part of each arm 20 and presses against the end of its rod 29. Handles 33 provide for turning the rods 32 so as to increase and decrease the pressure exerted between the arms 20 and the arms 9. This pressure opposes the pressure of springs 25. As explained in the Huck application previously mentioned, the net effect of the springs 25 and 28 is normally such as to reduce the pressure which would otherwise be applied to the doctor by the weight of the parts. Pressure gages 34, readable from outside the housings 9, are adjustably connected to the members 31, as in the Huck application.

Each arm 20 carries a stub shaft 40 which protrudes outwardly from a housing 9, passing through an opening 41 therein (Figs. 1A and 3). Outside the housings 9 the stub shafts 40 are each provided with an operating handle 42 and a catch 43, which cooperates with a stud 44 mounted on an upward extension 45 of each pedestal 13. Studs 44 may be adjustable as by means of eccentric mountings therefor. The upper extension 45 of each pedestal also carries an adjustable stop 46 which cooperates with a collar 47 concentric with shaft 40. Shafts 40

further carry eccentrics 48 which seat in depressions formed in blocks 49 attached to the housings 9 by means of bolts 50. With the handles 42 in the forward position as indicated in Figure 1A, the low point of eccentrics 48 will be facing the members 49, while retracting these handles (clockwise, Fig. 1A), will bring the high point of the eccentrics 48 against members 49.

The action of the parts just described is as follows: Assuming the parts to be in the operating position of Figure 1A and that it is desired to swing the doctor back from the cylinder, the handles 42 are first pulled backward. The effect of this is to disengage the hooks or latches 43 from studs 44, thus freeing arms 20 for backward (clockwise) movement. Further movement of the handles 42 causes the eccentrics 48 first to engage the blocks 49 and then to exert pressure thereagainst, forcing the arms 9 clockwise with relation to arms 20 by a small distance and lifting the doctor blade off the cylinder. This movement ordinarily need not exceed one-tenth of an inch or thereabouts. Arms 9 and 20 now being held together by engagement of the eccentrics 48 with the blocks 49, the shaft 11 is rotated (clockwise) by manipulation of the worm and gear unit 21 to swing the whole doctor assembly back from the cylinder. This involves a movement through approximately 60°. When restoring the doctor to operating position, worm and gear unit 21 is operated to rotate the shaft 11 counter-clockwise until collars 47 are brought against the adjustable stops 46. Handles 42 being still in their rearward position, the eccentrics 48 will still be holding back the arms 20 so that the doctor blade is held slightly off the cylinder and any possible damage is prevented. Handles 42 are now pushed into the position of Figure 1A, first gradually releasing arms 9 so that they may rotate counter-clockwise under the resultant effect of gravity and the combined action of springs 25 and 28, until the doctor is resting on the cylinder with the preset pressure and then engaging the hooks or latches 43 over the studs 44 to lock the mechanism in this position.

The worm and gear unit 21 for operating the shaft 11 is shown in detail in Figures 4 and 5 and comprises a housing 60 through which the shaft 11 passes and which carries in antifriction bearings a worm wheel shaft 61 operated by means of a counterbalanced crank 62. The worm 63 meshes with a worm wheel sector 64 fixed to the shaft 11 so that turning the crank 62 will rotate shaft 11 and move the doctor mechanism in the desired manner. The hub of the worm wheel sector 64 carries projections 65 to which poppet rods 66 are pivotally connected at 67. Each rod 66 extends into a socket 68 formed in the housing 60, the socket 68 being of larger diameter than the rod, as indicated, to accommodate pivotal movement of the rod. A thrust washer 70 reacts against the material of housing 60 surrounding the socket 68 and a cross plate or bar 71 seats against washers 72 fixed to the rods 66. Springs 73 are interposed between the plates 71 and thrust washers 70 tending to force the poppet rods 66 downwardly and thus tending to rotate the shaft 11 clockwise or in a direction to lift the doctor mechanism off the cylinder.

As will be apparent from Figure 1 of the drawing, the center of gravity of the parts carried by the shaft 11 is considerably displaced to the left of a vertical line through the center of the shaft, creating a moment due to the force of gravity, in a counter-clockwise direction in Figure 1. As

the shaft is rotated back from operating position, this moment will decrease sinusoidally, since the moment arm is proportional to the sine of the angle which a line, through the center of shaft 11 and the center of gravity of the supported parts, makes with the vertical. In consequence, for equal angular movements, the change in the gravity moment about the pivotal axis is greater at the beginning and decreases as the center of gravity approaches a position directly above the pivotal axis. Close counterbalancing requires that the counter moment due to the springs 73 will at all times be equal to and opposite in direction to that of the gravity moment, and that the actual change of moment be substantially sinusoidal. Such a characteristic of the spring counterbalance can readily be obtained with the construction shown in Figure 4 and in a very simple manner. As will be observed from that figure, clockwise movement of the shaft 11 causes expansion of the springs 73, reducing the force exerted thereby, substantially in proportion to the expansion, and with a resultant counter-balancing moment which changes in amount from a maximum, in the position shown in Figure 4, to zero at the time in the cycle when the center of gravity of the parts carried on the shaft 11 is directly over the axis of the shaft. At this time the springs 73 are neutral and exert no force as the snap rings 74, which are held in recesses in poppets 66, engage the upper ends of springs 73, the lower ends of which are resting on plate 71 which in turn is resting on ledges 75 of the housing 60. Further rotation of shaft 11, in a clockwise direction, will then compress springs 73 from above in a manner to counter-balance the weight of the parts carried on the shaft 11, as the center of gravity moves to the right of a vertical line through the axis of that shaft. Since the eccentrics 48 hold the doctor supporting arms and the doctor and associated parts in fixed relation to the operating arms throughout the movement to and from operating position, oscillation of these parts against the springs and consequent disturbance of balance is eliminated.

What is claimed is:

1. In a rotary intaglio doctor mechanism and in combination, a pivotally mounted doctor supporting arm, a pivotally mounted operating arm for swinging the supporting arm toward and away from a printing cylinder, an eccentric movably carried by the operating arm, the supporting arm having a cooperating surface positioned for engagement by said eccentric, the eccentric being located between the said cooperating surface and the printing cylinder, a stop limiting movement of the operating arm toward the cylinder, and means for moving the eccentric to engage the cooperating surface to hold the doctor supporting arm back from the cylinder and for moving the eccentric to disengage the cooperating surface and permit movement of the doctor supporting arm toward the cylinder.
2. Mechanism according to claim 1, comprising also a catch for holding the operating arm against the stop, the catch being connected to the eccentric for movement therewith.
3. In a rotary intaglio doctor mechanism and in combination, a shaft, an operating arm fixed thereto, an eccentric rotatably carried by the operating arm, a doctor supporting arm rotatably carried by the shaft for movement toward and away from a printing cylinder by the operating arm and having a cooperating surface positioned

for engagement by said eccentric, the eccentric being located between the said cooperating surface and the printing cylinder, a stop limiting rotation of the operating arm toward the printing cylinder, and means for turning the eccentric to engage the cooperating surface to hold the doctor supporting arm back from movement toward the cylinder and for turning the eccentric to disengage the cooperating surface and permit movement of the doctor supporting arm toward the cylinder.

4. Mechanism according to claim 3, comprising also a catch for holding the operating arm against the stop, the catch being connected to the eccentric for movement therewith.

5. In a rotary intaglio doctor mechanism, and in combination, a shaft, doctor supporting arms pivotally mounted on the shaft, operating arms fixed to the shaft, spring means acting between the doctor supporting arms and the said operating arms for regulating the doctor pressure, means for rotating the shaft to swing the doctor to and from operating position and spring means for counterbalancing the weight of the doctor and other parts carried by the shaft.

6. The combination according to claim 5, comprising also releasable means for holding the doctor supporting arms to the operating arms against movement toward a printing cylinder.

7. In a rotary intaglio doctor mechanism having a doctor pivotally mounted on a shaft for movement therewith by members fixed to the shaft and in which the printing pressure is adjusted by means of spring means acting between the doctor supporting arms and the said members, the combination with a means for rotating the shaft to swing the doctor to and from operating position, of spring means for counterbalancing the weight of the doctor and other parts carried by the shaft.

8. The combination according to claim 7, in which the counterbalancing spring means is con-

nected to the shaft so that it expands as the shaft is rotated to swing the doctor away from operating position, thus decreasing the spring force, and comprising also means varying the moment arm of the spring force about the shaft axis for maintaining the spring moment substantially equal to the gravity moment about the shaft.

9. In a rotary intaglio doctor mechanism and in combination, a shaft, an operating arm fixed thereto, an eccentric rotatably carried by the operating arm, a doctor supporting arm rotatably carried by the shaft for movement toward and away from a printing cylinder and having a cooperating surface positioned for engagement by said eccentric, the eccentric being located between the said cooperating surface and the printing cylinder, a stop limiting rotation of the operating arm toward operating position, and means for turning the eccentric to engage the cooperating surface to hold the doctor supporting arm back from operating position and for turning the eccentric to disengage the cooperating surface and permit movement of the doctor supporting arm toward operating position.

10. Mechanism according to claim 9, comprising also adjustable spring means acting between the operating arm and supporting arm for regulating the doctor pressure.

11. Mechanism according to claim 9, comprising also a catch for holding the operating arm against the stop, the catch being connected to the eccentric for movement therewith.
